(57) **CLAIM**

The ornamental design for a bottle holder, as shown and described.

DESCRIPTION

FIG. 1 is a front perspective of a bottle holder showing our new design;

FIG. 2 is a front perspective view of the bottle holder;

FIG. 3 is a top view of the bottle holder;

FIG. 4 is a bottom view of the bottle holder;

FIG. 5 is a back perspective view of the bottle holder;

FIG. 6 is a back view of one particular version of the bottle holder;

FIG. 7 is a front view of one particular version of the bottle holder;

FIG. 8 is a side view of the bottle holder;

FIG. 9 is an enlarged, partial, top perspective view of the bottle holder;

FIG. 10 is an enlarged, partial, alternate top perspective view of the bottle holder; and,

FIG. 11 is an exploded view of the bottle holder.

The broken lines showing a baby bottle in FIG. 1 illustrates environmental structure and forms no part of the claimed design.
